UNITED STATES PATENT OFFICE

154,830

DESIGN FOR A TOY PIG

Robert Y. Allen and Melvin Shaw, Beverly Hills,
Calif., assignors to Frank M. Hoover, Incorporated,
Youngstown, Ohio, a corporation of Ohio

Application May 7, 1948, Serial No. 146,229

Term of patent 7 years

(Cl. D34—2)

To all whom it may concern:

Be it known that we, Robert Y. Allen and Melvin Shaw, citizens of the United States, residing at Beverly Hills, in the county of Los Angeles and State of California, have invented a new, original, and ornamental Design for a Toy Pig, of which the following is a specification, reference being had to the accompanying drawing, forming a part thereof.

The right side of the toy pig is a substantial duplicate of the left side thereof.

We claim:

The ornamental design for a toy pig, as shown and described.

ROBERT Y. ALLEN.
MELVIN SHAW.
